HANDLE FOR KITCHEN TOOLS OR SIMILAR ARTICLES

George A. Cushing, Des Plaines, Ill., assignor to Ekco
Products Company, Chicago, Ill., a corporation of Delaware

Filed Apr. 25, 1962, Ser. No. 69,851

Term of patent 14 years

(Cl. D44—29)

FIG. 1.

FIG. 2.

FIG. 1 is a top plan view of a handle for kitchen tools or similar articles, showing my new design, the essential features thereof being shown in full lines, the handle being of conventional configuration; and

FIG. 2 is a side elevational view thereof showing the conventional thickness of the handle.

I claim:

The ornamental design for a handle for kitchen tools or similar articles, as shown and described.
